RECEIPT ENVELOPE

Lawrence P. Woodward, Evanston, Ill., assignor
to William Cherney, Chicago, Ill.

Application February 13, 1933, Serial No. 656,482

2 Claims. (Cl. 229—70)

This invention relates to mailing envelopes, and among other objects aims to provide means for simplifying certain business transactions such for example as the handling of bank deposits by mail.

The nature of the invention may be readily understood by reference to one illustrative embodiment thereof shown in the accompanying drawing.

10 In said drawing:

Fig. 1 is an elevation of the envelope open to present a rectangular sheet for insertion in a typewriter or the like;

15 Fig. 2 is an elevation of the face of the envelope opposite that shown in Fig. 1;

Fig. 3 is a transverse section to illustrate the location of the envelope pocket; and

20 Fig. 4 is a view illustrating one function of the address appearing on the outer face of the envelope flap.

The invention is here shown embodied in an envelope used to facilitate handling of bank deposits by mail. Because of the diminishing number and soundness of outlying banks, the handling of bank deposits by mail has become an increasingly onerous problem for the larger central banks. Business of this character when transacted by ordinary methods is expensive and unprofitable, yet it cannot ordinarily be refused.

30 The present invention affords a means for simplifying and reducing the cost of transacting such business to a point where it may become profitable and thereby worth promoting.

The illustrative envelope comprises an envelope 35 pocket 10 of rectangular shape wherein the back face 11 of the pocket is also substantially rectangular in shape and presents an unbroken or uninterrupted surface from edge to edge of the pocket which may receive printing or typewriting 40 in any portion of its surface. To that end, the joints between the portions of the sheet forming the envelope pocket occur at the side edges 12 of the pocket and not within the area of the rear face 11 which therefore presents no joints nor 45 broken surfaces (as the case in the ordinary envelope) to make it impracticable for use in a typewriter or in a press. In this connection it should be noted that in practice printed forms are printed on blank envelopes taken from stock and 50 after they have been made up, and therefore even

as to printing joints or variations in thickness of the area printed upon, are objectionable. The free edge 13 of the pocket is straight and terminates substantially with the edge of the pocket itself, namely at the hinge 14 of the flap 15.

The flap 15 is likewise substantially rectangular in shape and corresponds substantially in size to the face 11 of the pocket, and when opened out the face 11 and the inner face 16 of the pocket present a rectangular sheet comprising two flat surfaces each of which may be readily typed upon without danger of illegible typing or imperfect alinement at any point. Along the edge 17 of the flap is a relatively narrow band of adhesive adapted to adhere to the outer margin 18 of the face 11, thereby sealing the envelope as well as covering any written material appearing upon the face 11.

The face 11 has printed thereon an appropriate form for use as the equivalent of a deposit slip in 20 the bank. The arrangement of the form of the deposit slip may vary in accordance with the practice in the particular bank employing the envelope. The arrangement of the form is preferably such as to promote convenience in entering 25 items therein either on a typewriter or by hand. Rules, notices, etc for the attention of the depositor may be printed in the area 18. These serve their purpose before they are covered by the adhesive on the flap.

The face 16 of the flap also has printed thereon a form which serves as the equivalent of a duplicate deposit slip, namely as a signed and dated acknowledgment by the bank of receipt of the deposit and the amount thereof. Here also the particular form of the receipt may vary in accordance with the practice in the bank employing the envelope. Preferably a space should be provided on which may be imprinted the bank's receipt stamp 19 which usually bears the date of receipt of the deposit. It should also provide a place for the initials or countersignature 20 of an authorized employee or officer of the bank.

Upon the opposite face 21 of flap 15 appears the address 22 of the depositor sending the deposit. This address is so located on the flap that it is in position to register with the window 23 of a window envelope 24 enclosing the deposit envelope. The word "From" also preferably appearing on 45 50

the face 21 is so located that it will not register in the window envelope.

The front face of the envelope bears, preferably printed thereon, the address 25 of the bank employing the envelope in its mail deposit business, being the address to which the deposit is sent.

The above described envelopes may be advantageously employed by the bank in the following manner to facilitate handling of mail deposits: 10 The address 22 of the given depositor is first placed by the bank on the outer face 21 of the flap. This is most conveniently done by employing the address plates usually made by the bank for each depositor. If desirable a separate set of 15 address plates may be made for depositors forwarding deposits by mail. These envelopes are inserted in a slightly larger envelope 24 with the address 22 registering with the window in the envelope. The envelope 24 is also preferably employed to enclose to the depositor the deposit 20 receipt for the previous deposit. The depositor employs the envelope to mail the succeeding deposit to the bank, preferably filling out the deposit slip form on the rear face of the envelope 25 pocket. When the cover flap is sealed down the envelope is ready to mail merely by affixing a postage stamp, since the bank's address and the depositor's return address appear on the front and rear faces of the envelope respectively. 30 There is no opportunity for error since both addresses have been placed legibly thereon by the bank.

Upon receipt of the envelope containing the deposit the flap is opened by breaking the line of adhesive along the margin 18, the deposit checked on the deposit slip form, and the amount entered (if this has not already been done) on the receipt form on the back of the flap which is then initialed or counter-signed and stamped with the bank's receipt stamp 19. Thereupon the flap which is detachable along the hinge line 14, is detached and returned to the depositor with a fresh deposit envelope. To secure added neatness the flap may be press perforated or otherwise weakened along the line 26 adjacent the adhesive, to permit the adhesive margin (rendered irregular by unsealing) to be torn off prior to return to the depositor. Until such detachment all papers are connected together in a single unit and loss prior to making necessary entries is therefore impossible.

The receipt or duplicate deposit slip is sufficiently identified by reason of the fact that the depositor's name necessarily appears on the opposite face of the slip which was formerly the flap of the envelope. There is no opportunity for omission of the address since the depositor's address must have been placed thereon in order for the envelope to have reached the depositor. 55 If desired the deposit slip form or face 11 may be arranged so that the place 27 for the depositor's name and address may be made to register with the name and address 22 on the outer face of the flap, thereby making it possible by the use 60 of an interposed sheet of carbon paper, to enter the depositor's name and address simultaneously on the deposit slip and on the flap which for this purpose would be placed in register and inserted in a typewriter or addressing machine.

70 The envelope pocket 10 from which the flap has been detached is retained by the bank, the pocket being used if desired to hold the deposit until it has been appropriately checked. It is important to note that the portion of the envelope retained 75 by the bank bears the post office date stamp 28

placed thereon by the post office (i. e. an agency independent of the bank) to indicate when the envelope passed through the post office. This indicates the approximate date on which the deposit was received by the bank, but more important it serves, in the event of dispute, to establish the approximate date on which the deposit left the hands of the depositor. The bank is thus protected by an independent agency from claims by the depositor that the deposit had been mailed 10 at an earlier date. Of course it correspondingly safeguards the depositor against an erroneous or post-dated date stamp of the bank.

An identifying mark or band 29 may be placed on the envelopes so that they may be readily separated from other mail delivered to the bank.

The foregoing description serves sufficiently to indicate the character of uses to which envelopes embodying the invention may be put. It embodies a rectangular sheet presenting surfaces, 20 any part of which may receive printing and type-writing and comprising a surface (i. e., the back of the envelope pocket) upon which an appropriate account or statement may be made, and a detachable sheet bearing the correct address of 25 the individual who mailed the envelope. The individual receiving the envelope and retaining the pocket portion thereof possesses the evidence (i. e. the post office date stamp) which protects both the sender and the receiver and avoids controversy. The unitary character of the device and the means by which error is avoided both in addresses and dates, is obviously of great importance in transactions such as those above described and analogous transactions.

Obviously the invention is not limited to the details of the illustrative construction since these may be variously modified. Moreover it is not indispensable that all features of the invention be used conjointly since various features may be 40 used to advantage in different combinations and sub-combinations.

Having described my invention, I claim:

1. A mailable receipt envelope for making bank deposits by mail comprising in combination a 45 closed rectangular envelope pocket, the rear face of which is formed by an integral sheet having an uninterrupted surface extending substantially throughout the area of the rear face of said pocket and presenting a surface which may be 50 printed upon after formation of the envelope, the joints forming the closed pocket lying at the edges of said pocket, and a substantially rectangular sealing flap of a size to cover substantially the entire rear face of said pocket, said rear face 55 and flap when unfolded being adapted to be inserted in an imprinting device and presenting smooth surfaces to be imprinted upon.

2. A mailable receipt envelope for making bank deposits by mail comprising in combination a 60 rectangular envelope pocket closed on three of its four sides adapted to carry banking deposits, said envelope carrying along its open side a substantially rectangular sealing flap of substantially the size of the envelope, said flap being made detachable from the envelope along the line of its open side, both faces of said pocket presenting smooth faces unbroken by points whereby the envelope may be printed upon after formation, the joints forming the pocket lying at the edges of said 65 pocket, the rear face of said envelope pocket carrying a deposit slip form spaced above the bottom edge of said face to provide a sealing area, said flap carrying on its inner face at its lower free edge an area of adhesive adapted to register 70

with said sealing area, said flap being also detachable from said adhesive area along a line just above said adhesive area, the inner face of said detachable flap carrying a receipt or duplicate deposit slip form adapted to carry acknowledgement from the bank of the deposit, the outer face of the said flap carrying the address of the sender in position to appear through the window of a

window envelope, and the front face of the envelope pocket carrying the address of the bank and adapted to receive a post-office date stamp to indicate approximate date of receipt by the bank, said flap being adapted to be detached and returned to the depositor whose name appears on the outer face of the flap.

LAWRENCE P. WOODWARD.

CERTIFICATE OF CORRECTION.

Patent No. 1,985,592.

December 25, 1934.

LAWRENCE P. WOODWARD.

It is hereby certified that error appears in the printed specification of the above numbered patent requiring correction as follows: Page 2, second column, line 48, claim 1, for "iuninterrupted" read uninterrupted; and line 68, claim 2, for "points" read joints; and that the said Letters Patent should be read with these corrections therein that the same may conform to the record of the case in the Patent Office.

Signed and sealed this 19th day of February, A. D. 1935.

with said sealing area, said flap being also detachable from said adhesive area along a line just above said adhesive area, the inner face of said detachable flap carrying a receipt or duplicate deposit slip form adapted to carry acknowledgement from the bank of the deposit, the outer face of the said flap carrying the address of the sender in position to appear through the window of a

window envelope, and the front face of the envelope pocket carrying the address of the bank and adapted to receive a post-office date stamp to indicate approximate date of receipt by the bank, said flap being adapted to be detached and returned to the depositor whose name appears on the outer face of the flap.
